ATTORNEY

UNITED STATES PATENT OFFICE

127,318

DESIGN FOR A TOY AIRPLANE

James Edward Durden, Los Angeles, Calif.

Application February 14, 1941, Serial No. 99,008

Term of patent 3½ years

To all whom it may concern:

I, James Edward Durden, a citizen of the United States, residing at Los Angeles, in the county of Los Angeles, State of California, have invented a new, original, and ornamental Design for a Toy Airplane, of which the following is a specification, reference being had to the accompanying drawing, forming a part thereof.

Fig. 1 is a perspective view of the toy airplane, showing my new design, the shading on the surfaces of the propeller, wings and em-

pennage representing the direction of extension of the barbs from the quill of natural feathers as used in the design;

Fig. 2 is a side elevation of the design, on a slightly smaller scale than Fig. 1; and Fig. 3 is a front elevational view thereof.

I claim:

The ornamental design for a toy airplane, substantially as shown.

JAMES EDWARD DURDEN.
